UNITED STATES PATENT OFFICE

100,195

DESIGN FOR AN ELECTRIC ROLL BAKER OR SIMILAR ARTICLE

William Dallas Bellamy, Henderson, Tex., assignor of one-half to Ollie Thompson Brightwell, Henderson, Tex.

Application February 27, 1936, Serial No. 61,393

Term of patent 7 years

To all whom it may concern:

Be it known that I, William D. Bellamy, a citizen of the United States, residing at Henderson, in the county of Rusk and State of Texas, have invented a new, original, and ornamental Design for an Electric Roll Baker or Similar Article, of which the following is a specification, reference being had to the accompanying drawing, forming part thereof.

I claim:

The ornamental design for an electric roll baker or similar article as shown.

WILLIAM DALLAS BELLAMY.
